UNITED STATES PATENT OFFICE.

BENJAMIN D. RADCLIFFE, OF CHICAGO, ILLINOIS, ASSIGNOR TO AMERICAN LOCK NUT COMPANY, A CORPORATION OF NEW YORK.

LOCK-NUT.

1,143,229.

Specification of Letters Patent. Patented June 15, 1915.

Application filed September 22, 1913. Serial No. 791,242.

To all whom it may concern:

Be it known that I, BENJAMIN D. RADCLIFFE, a citizen of the United States, residing at Chicago, in the county of Cook and 5 State of Illinois, have invented certain new and useful Improvements in Lock-Nuts, of which the following is a specification.

My invention relates in general to lock nuts, and more particularly to lock nuts of 10 the type covered by U. S. Patent 986,446, granted March 14, 1911, to Chester T. Drake.

The primary object of my invention is to provide a lock nut of the character referred to, with a device for holding the locking key 15 within the recess in the nut while the nut is being applied to the bolt, thereby facilitating the application of the nut to the bolt by preventing the accidental displacement of the locking key.

20 A further object of my invention is to provide a lock nut of the type having a recess loosely containing a rolling locking key, with a device for holding the key within the recess in such position that the locking collars on the key will aline with the threads 25 of the nut, and consequently aline with the groove between adjacent convolutions of the threads of the engaged bolt, so as to permit the ready application of the nut to the bolt.

30 A still further object of my invention is to provide a lock nut of the character referred to, with a device for insuring the locking of the nut upon the bolt when there is a considerable loose fit between the nut 35 and bolt, as is frequently the case.

A final object of my invention is to provide an improved lock nut which will be simple in construction, convenient in use, and efficient in operation.

40 My invention will be more fully disclosed hereinafter with reference to the accompanying drawing, in which the same is illustrated as embodied in several convenient and practical forms, and in which—

45 Figure 1 is a longitudinal central section through a nut provided with the preferred form of my invention. Fig. 2 is an elevational view looking from the left in Fig. 1. Fig. 3 is a perspective view of the locking 50 key and supporting device therefor removed from the nut; and Fig. 4 is a perspective view of the key-supporting device.

Similar reference characters are used to designate similar parts in the several figures of the drawing.

Reference letter A indicates a nut, which may be of any desired size, shape, and material. A longitudinal recess *a* is formed in the nut, such recess opening inwardly and interrupting the thread of the nut. This recess is formed of different depths to permit the movement of the key therein into and out of locked relation with the bolt in the manner fully illustrated and described in said prior patent to Drake No. 986,446.

B designates a locking key loosely fitting within the recess *a* in the nut and provided with one or more radial locking collars *b'* and *b''*, one of such collars being preferably located at each end of an intermediate concentric 70 connecting portion of less diameter than the diameter of the collars.

The lock nut above described does not in itself constitute my present invention, but is illustrated and described in order that the 75 operation of my invention may be fully disclosed.

Referring to the drawings, C designates a supporting device for the key, such device being preferably formed of sheet metal having sufficient resiliency to retain the device within the recess *a* in the nut. One or both edges of the device C may be provided with serrations *c* to more securely grip the radial walls of the recess *a*, and thereby retain the 85 device securely within the recess. The material of which the holding device C is formed possesses sufficient resiliency to permit the ready insertion of the device within the recess in the nut. The holding device 90 is provided with clips *c'* and *c''*, preferably formed integral with the metal plate of which the device is formed, and bent backwardly so as to loosely surround the reduced intermediate portion of the key B. The 95 holding device C is provided with a spring *d*, which engages the key and tends to lift the same toward the center of the nut. The spring *d* is preferably formed integral with the plate of which the holding device is 100 formed, and may be conveniently struck from the metal plate forming the device.

The manner of using and operation of the holding device above described is as follows:

The key B is inserted between the plate C and the clips c' and c^2 in the manner shown in Fig. 3. The holding device and key supported thereon are then inserted in the recess a of the nut by slightly compressing the holding device, the resiliency of the metal then serving to cause the edges of the device to tightly grip the opposing radial walls of the recess a and firmly retain the key within the recess in the nut. The holding device is so located within the recess in the nut as to aline the locking collars of the key with the convolutions of the screw threads in the nut. The nut may then be readily applied to the bolt without danger of the key becoming accidentally displaced from the recess in the nut, and without danger of the locking collars on the key engaging the thread of the bolt, inasmuch as the alinement of the collars with the thread of the nut insures the alining of the collars with the grooves between adjacent convolutions of the thread on the bolt. The spring d lifts the key toward the center of the nut so that it will frictionally engage the bolt and insure the movement of the key into the restricted portion of the recess a and tightly lock the nut on the bolt against any relative rotation in a direction to disengage the nut from the bolt. The spring on the holding device therefore serves to secure the locking of a nut on a bolt, even when there is considerable looseness in the engagement of the nut and bolt.

From the foregoing description it will be observed that I have invented an improved device for facilitating the application of a lock nut to a bolt and for increasing the efficiency of the locking key. Through the use of my invention the key is retained within the recess in the nut and in proper position to permit the application of the nut to a bolt; and in the preferred form of my invention it further serves to yieldingly lift the key toward the center of the nut so as to insure the locking of the nut upon the bolt even when there is a considerable difference in the diameters of the bolt and nut.

I claim:—

1. The combination with a lock nut having a recess therein, of a key having locking collars thereon loosely supported in said recess, and a sheet metal device resiliently supported within said recess and having a clip thereon loosely surrounding the key to retain the same within said recess and to permit its movement into locked and unlocked positions relatively to the thread on the bolt, the said device also having a spring thereon engaging said key to lift the same into contact with the threads on the bolt.

2. The combination with a lock nut having a recess therein, of a key having spaced locking collars thereon loosely supported in

said recess, and a key retaining device 65 formed of resilient sheet metal sprung into said recess and held therein by the engagement of its opposite edges with the opposite side walls of said recess, said device having a clip cut therefrom and bent loosely around 70 said key to retain the same within said recess and to permit movement thereof into locked and unlocked positions relatively to the bolt.

3. The combination with a lock nut having a recess therein, of a movable key having spaced locking collars thereon loosely supported in said recess, and a sheet metal device resiliently supported within said recess and having clips thereon loosely surrounding 80 the key intermediate of said spaced collars to retain the key within said recess and to permit its movement into locked and unlocked positions relatively to the thread of the bolt.

4. The combination with a lock nut having a recess therein, of a key having spaced locking collars thereon loosely supported in said recess, and a sheet metal device resiliently supported within said recess and having clips thereon loosely surrounding the key intermediate of said collars to retain the key within said recess and to permit its movement into locked and unlocked positions relatively to the thread on the bolt, the 95 said device also having a spring thereupon engaging said key intermediate of said collars to lift the same into contact with the threads on the bolt.

5. The combination with a lock nut having a recess therein, of a key having spaced locking collars thereon loosely supported in said recess, and a key-retaining device formed of resilient sheet metal sprung into said recess and held therein by the engagement of its opposite edges with the opposite side walls of said recess, said device having clips cut therefrom and bent loosely around 105 said key to retain the same within said recess and to permit the movement thereof into locked and unlocked positions relatively to the bolt, the said device also having a resilient tongue cut therefrom and engaging said key to lift the same into contact with the bolt.

6. The combination with a lock nut having a recess therein, of a movable key loosely supported in said recess, and a sheet metal device resiliently supported within said recess and having clips thereon loosely surrounding the key to retain the same within said recess and to permit the movement of said key into locked and unlocked positions.

7. The combination with a lock nut having a recess therein, of a key loosely supported in said recess, and a sheet metal device resiliently supported within said recess and having clips thereon loosely surround-

ing the key to retain the same within said recess and to permit the movement of said key into locked and unlocked positions, the said device also having a spring thereon 5 engaging said key and tending to lift the same toward the center of the nut.

In testimony whereof, I have subscribed my name.

BENJAMIN D. RADCLIFFE.
